UNITED STATES PATENT OFFICE.

JOHN C. NICHOLS, OF SHEBOYGAN, WISCONSIN.

TRACE SUPPORT.

Application filed May 22, 1923. Serial No. 640,683.

To all whom it may concern:

Be it known that I, JOHN C. NICHOLS, a citizen of the United States, and resident of Sheboygan, in the county of Sheboygan and 5 State of Wisconsin, have invented certain new and useful Improvements in Trace Supports; and I do hereby declare that the following is a full, clear, and exact description thereof.

10 This invention relates to strap guiding member for harness and is particularly directed to a trace support.

This case constitutes one of a series of cases filed simultaneously having elements 15 cooperating to form a harness without stitching.

In trace supports there is a great deal of wear between the trace and the supporting straps as usually constructed. Also at this 20 point it is highly desirable that projecting parts be kept away from the horse as the trace straps impose considerable pressure at times laterally upon the side of the horse, and it is, therefore, highly desirable to provide a device free from projecting portions which might injure the horse. Also when 25 the straps and traces are under considerable stress binding frequently occurs with consequent displacement of parts of the harness.

30 This invention is designed to overcome the above noted defects, and objects of such invention are, therefore, to provide a trace support in which metal is provided for the trace to slide upon, in which contact of 35 leather to leather is avoided, in which no laterally projecting portions likely to injure the horse are employed, in which a portion of the device is encircled by the supporting strap, and in which means are provided for 40 permitting the entering of the trace into the device without the necessity of threading the end of the trace through the support.

Further objects are to provide a device which may be readily cast in a simple manner 45 without necessity of providing elaborate cores and to provide a device which may be cheaply and readily manufactured at a small cost.

An embodiment of the invention is shown 50 in the accompanying drawings, in which;

Figure 1 is a face view of the trace support.

Figure 2 is a sectional view on the line 2-2 of Figure 1.

55 Figure 3 is an edge view of the device.

Figure 4 is a longitudinal sectional view showing the supporting strap in position.

Figure 5 shows a modified use of the device illustrating its adaptability to old harnesses.

Figure 6 is a detailed modification of the support.

The device comprises a main body portion of metal which is provided with a vertical wall 1. This wall has a laterally projecting portion 2 adjacent its upper end and a laterally projecting portion 3 adjacent its lower end.

It is provided with an aperture 4 therethrough for a purpose thereafter to appear.

The lower or bottom member 3 is provided with an upturned tongue 5 which roughly parallels the vertical wall 1. The vertical wall 1, the tongue 5 and the upper and lower portions 2 and 3 define a rectangular opening for the reception of the trace 6 as shown in dotted lines in Figures 4 and 5.

The trace, it will be seen, freely slides through the rectangular aperture in the device with a minimum friction and without any contact whatsoever of leather to leather, thereby avoiding rapid wear.

It is to be noted that by ending the tongue 5 a distance below the upper portion 2 that an entrance aperture is provided through which the trace may be readily passed without the necessity of threading one end of the trace through the device.

The lower end of the body portion is provided with an eyelet consisting of an outer loop 7 and an inner member 8, such inner member being spaced from the end of the body portion. The eyelet is adapted to receive the belly band or buckle therefrom.

Side walls 9 extend upwardly from the transverse upper portion 2 and are joined by bars 10 and 11, such bars being arranged in spaced relation with the bar 10 uppermost. These bars have their substantially flat inner faces arranged in planes which substantially converge, as may be clearly seen from Figure 4. In using the device the trace is entered through the side opening between the tongue 5 and the upper portion 2. The supporting strap extends downwardly between the body portion and the bar 11 over the outer face of the tongue 5 beneath the lower portion 3 adjacent the outer face of the wall 1 and upwardly beneath the bar 10, thus de-

fining a loop encircling the body portion of the device and spaced from the trace 6 by means of such body portion, thereby preventing a leather to leather contact and providing an unobstructed metal slide way for the trace.

It is to be noted from Figure 4 that although great stresses may be imposed upon the device, that the major portion of the 10 trace support is completely encircled by the supporting strap 12 and consequently no portion of the support is called upon to bear excessive strains.

It is found in manufacturing the trace support that by the provision of the aperture 4 in the wall 1 that a simple form of mould may be employed, as the moulding sand may project to the inner face of the tongue 5. This, it will be seen, avoids the 20 necessity of elaborate cores for moulding the device and allows, therefore, a very cheap method to be followed in manufacturing the device.

Figure 5 shows the manner of using the 25 device when it is applied to old harness in which it is desired to employ the old parts of the straps without in any way altering them. This is readily accomplished by inverting the trace support, as shown in 30 Figure 5, with the eyelet portion uppermost. In this case, the belly band 13 is passed upwardly under the bar 11 around the laterally projecting portion 3, downwardly on the outer side of the wall 1 and is wrapped 35 or folded over the bar 10. A rivet 14 is then passed through the end of the strap and the adjacent portion, as shown in Figure 5, to securely lock the strap in position. When the device is used in the manner de- 40 scribed for the repair of old harness, it will be seen that a metal slide way is still provided for the trace although the device

functions in a different manner from that previously described.

Figure 6 illustrates another form of the 45 support wherein the back wall is made solid and the tongue 5 is of a corresponding width thereto.

It will thus be seen that a trace support has been provided which is admirably adapted for the guiding of the trace and that it offers a minimum of friction to the free sliding of the trace. It will also be seen that the trace support may be employed without requiring any stitching whatsoever 55 of the adjacent portions of the harness and that projecting portions which might damage the horse are wholly avoided.

I claim:

1. A trace support comprising a body portion having an eyelet at one end, a vertical wall having laterally projecting portions, a tongue extending from one of said portions and roughly paralleling said wall and spaced therefrom, and means for guiding and retaining a strap in encircling relation to said body portion. 60

2. A trace support comprising a body portion having a vertical wall, projecting portions extending laterally from the upper and lower ends of said wall, a tongue extending upwardly from said lower portion and spaced from said wall to form a guiding channel for said trace, an eyelet extending downwardly from said body portion and having its inner end spaced from the lower end of said body portion, and a pair of guide bars located adjacent and spaced from the top of said body portion. 70

In testimony that I claim the foregoing 80
I have hereunto set my hand at Milwaukee,
in the count of Milwaukee and State of
Wisconsin. 75

JOHN C. NICHOLS.
